Fig. 1.

UNITED STATES PATENT OFFICE

2,079,876

PAPER CONTAINER

Henry J. Reiter, Philadelphia, Pa., assignor to
 Brown & Bailey Company, Philadelphia, Pa., a
 corporation of Pennsylvania

Application December 11, 1936, Serial No. 115,295

6 Claims. (Cl. 229—37)

This invention relates to disposable containers, especially milk bottles and the like, made of paper or cardboard and impregnated with a water-proofing agent before they are filled and sealed to condition them for the market and includes certain improvements whereby such containers can be so made as to retain the requisite impermeability to their fluid contents for a relatively long period, the invention being of especial utility when embodied in a paper bottle of the general character of that forming the subject of my pending application for U. S. Letters Patent, Serial No. 91,353, filed July 18, 1936.

Thus a principal object of the invention is to provide in a bottle manufactured from a paper or cardboard blank certain improvements which enhance the effectiveness of the glued seam which secures together the two sides of the bottle formed by opposed end portions of the blank.

Another object of the invention is to provide a bottle blank having an area adapted to receive the adhesive in a smooth unbroken film, and a glue lap adapted for cooperation with said area to form a bottle of improved construction facilitating the subsequent formation of a satisfactory and effective top closure therefor after the bottle is filled.

Other objects, purposes and advantages of the invention will hereinafter more fully appear or will be understood from the following description of a preferred embodiment thereof illustrated in the accompanying drawing, in which:

Fig. 1 is a plan view of the blank of which the bottle is made and having thereon the adhesive employed for uniting its sides.

Fig. 2 is a perspective view of the bottle formed therefrom with its top closure sealed and thus ready to be placed on the market.

Fig. 3 is a diagonal elevation of the bottle prior to being filled with the milk or other fluid it is to contain, the front portion being broken away to show the interior construction.

Fig. 4 is a fragmentary enlarged interior diagonal elevation of the upper front corner of the bottle after the sealing of the top closure as shown in Fig. 2.

Fig. 5 is a further enlarged fragmentary vertical section of the bottle on the line 5—5 in Fig. 3.

Fig. 6 is a similarly enlarged fragmentary section of the blank on the line 6—6 in Fig. 1 and showing in detail the nature of the score lines impressed therein.

In the several figures like characters are used to designate the same parts, the sections are tak-

en in the direction of the arrows on the section lines, and the scores indented in the blanks are indicated in dot and dash lines in Figs. 1, 3 and 5.

More particularly, the blank B shown in Fig. 1 comprises four side panels 1, 2, 3 and 4 arranged side by side and defined from each other by vertical scores 5, 6 and 7. A glue lap 8 projects from the free edge of the panel 1 from which it is defined by a score 9, and its bottom tab 10 extends slightly beyond the end of the panel at its lower end. The side panels also have bottom flaps 12 defined from their lower edges by transverse scores 13 and adapted to be folded inwardly, with the tab 10, and secured in the usual way to make a bottom for the bottle after the side panels have been folded up and the glue lap 8 glued to the panel 4.

The upper ends of the glue lap and side panels carry extensions 14—18 inclusive, separated from these parts by a transverse score 19 which extends entirely across the glue lap and the panels 1, 2 and 3 but terminates in the panel 4 at a point 20 short of the free edge of the panel by about the width of the glue lap 8. At its opposite end the score 19 in crossing the glue lap is preferably continued as a "knife score" 21, that is the fibers of the stock are cut on that side of the blank corresponding to the outer surface of the bottle but left uncut on the opposite surface as clearly appears from Figs. 4 and 5 and as hereinafter more fully explained. Adjacent their upper edges the extensions 15, 16 and 17 are traversed by a score 22 which in prolongation also extends across the extension 18 to a point 23 short of its free edge and spaced therefrom a distance approximating the spacing of the point 20 at the corresponding end of the score 19.

The upper ends of the extensions 15 and 17 on the panels 1 and 3 are provided with locking tongues 24, 25 the first of which is separated from extension 15 by a score 26 while the extension 16 on panel 2 is provided with angular scores 27, 28 and a short central vertical score 29 extending upwardly from their point of intersection to facilitate the folding of extension 16 between extensions 15 and 17 in forming the top closure. The extension 18 on panel 4 is also provided with an angular score 30 and a central vertical score 31 adjacent its upper edge respectively corresponding to the scores 27 and 29 and with another angular score 32 which extends from the intersection of the score 30 with the lower end of the score 31 downwardly toward the upper corner of the panel 4. The score 32 however, terminates short of the corner of the

panel at a point 33 in alignment with the points 20 and 23 at the ends of the horizontal scores 19 and 22. Preferably also the score 13^a between the panel 4 and its bottom flap is terminated at a point 35 short of the free edge of the panel 4 in the same manner, so that the panel, its extension 18 and bottom flap 12 present for approximately the width of the glue lap and throughout their combined lengths a smooth, continuous surface which is unbroken and unobstructed by the ridges produced in other parts of one face of the stock by the scores impressed therein.

These scores are formed by pressing the stock 15 between dies or by other mechanical means which form grooves X on one side of the stock and corresponding ridges Y on the opposite side, as clearly shown in Fig. 6, the ridges Y usually being disposed on the face which is to become 20 the inside of the bottle in order to enhance its exterior appearance. When an area of the blank to which the adhesive is to be applied is traversed by scores of this character, the glue wheel or other adhesive applying mechanism is deflected by the ridges Y and fails to contact or improperly 25 contacts a portion of the stock adjacent thereto with the result that a smooth and uniform layer of adhesive cannot be deposited throughout the area so that when some other part of 30 the blank is brought against it to form a glued seam, those portions of it which have been skipped or improperly traversed by the glue wheel do not adhere properly to the other part and a leaky seam frequently results.

35 However, when in accordance with my invention the area to which the adhesive is to be applied, namely that adjacent the free edge of the panel 4, its extension 18 and the upper part of its bottom flap 12, is free of scoring and therefore entirely smooth and flat, a strip or film of adhesive 36 may readily be deposited thereon in a uniform continuous layer and when the blank is thereafter formed up the glue lap 8 is therefore held securely thereto throughout its 45 entire length.

The knife score 21 in the glue lap and near it an angular cut 37 extending entirely through the stock but terminating slightly short of the lateral edges of the glue lap are preferably provided in the blank in accordance with the disclosure of my said application, the angularity of this cut corresponding to that of the score 32 of which the cut is thus, in effect, a prolongation beyond the point 33 when the glue lap is brought 50 into contact with the adhesive 36 in forming up the blank. The knife score 21 is then also aligned with and in prolongation beyond the point 20 of the transverse score 19 and thus although a double thickness of material is provided where the glue lap contacts the panel 4 and its extension, the glue lap is weaker at the knife score and cut than elsewhere and as it is firmly secured to the panel 4 and its extension throughout its area it constrains these parts 55 to bend along lines registering with the knife score and cut respectively when mechanically folded in forming the top closure.

Thus as shown in Fig. 4, the knife score 21 spreads in folding to form a V-shaped notch 70 opening toward the panel 4 and the angular cut 37 forms a V-shaped groove or slot opening in the opposite direction, thereby affording sufficient yieldability in the glue lap to prevent tearing of the stock or excessive strains on the material in localized areas. If, as is usually the 75

practice, the bottle is coated interiorly and exteriorly with a water-proofing agent prior to its being sealed the surfaces of the stock as well as the edges of the cut and knife score become impregnated with it so that the subsequent opening of the notch and groove as the top closure is formed presents no new and unimpregnated surfaces for contact with or absorption of the bottle contents.

It will now be apparent that my invention may 10 be advantageously embodied in bottles of various types, among others, that shown in Patent 2,025,477 to Henry T. Scott, December 24, 1935 since its insures proper adherence of the glue lap throughout its length to the other parts of 15 the bottle, and, further, for the reasons herefore explained, that the invention is of particular utility when embodied in bottles of the type disclosed in my said application and thus comprising the knife score and cut to which I 20 have herein referred.

It will of course be understood the foregoing description and accompanying drawing are but 25 illustrative of one manner of practising the invention and that various changes and modifications may be made therein if desired without departing from the spirit and scope thereof as defined by the appended claims.

Having thus described my invention, I claim and desire to protect by Letters Patent of the 30 United States:

1. A bottle formed of foldable sheet material comprising a plurality of integral side panels each having a bottom flap on one of its ends and an extension on its opposite end respectively defined therefrom by transverse scores, the transverse scores defining one panel from its extension and bottom flap terminating short of one of its longitudinal edges, said extension having an angular score directed toward a point on said 35 edge aligned with the score extended defining the extension from the panel but terminating short of said edge in alignment with the corresponding ends of said transverse scores, an adhesive film coating the entire length of said panel 40 and extension between said edge and the adjacent ends of said scores, and a glue lap integral with another panel and its extension engaging said adhesive film throughout its length.

2. A bottle formed of foldable sheet material 50 comprising a plurality of integral side panels each having a bottom flap on one of its ends and an extension on its opposite end, a glue lap carried by a side edge of one panel and its extension, the bottom flap on an adjacent panel being defined therefrom by a transverse score terminating short of a side edge of the panel a distance substantially corresponding to the width of the glue lap, the extension of the last mentioned panel being defined therefrom by a similar score 55 and having an angular score directed toward a point on said edge aligned with said last mentioned score but similarly terminating short of said edge, and a continuous film of adhesive interposed between the glue lap and said last mentioned panel and its extension between the ends of said scores and said side edge.

3. A bottle formed of foldable sheet material comprising a plurality of integral side panels each having a bottom flap on one of its ends and 70 an extension on its opposite end, each panel and its extension being hinged to an adjacent panel and its extension, three of the latter being fully defined from their adjacent panels by a transverse score extending across said panels and 75

- partially across a fourth panel to thereby partially define its extension therefrom, a glue lap defined from one of the first mentioned panels by a longitudinal score and having a transverse score and a cut extending angularly upwardly from adjacent the intersection of said longitudinal score and the knife score, and a film of adhesive interposed between the glue lap and the
- 5 knife score in prolongation of said transverse score and a cut extending angularly upwardly from adjacent the intersection of said longitudinal score and the knife score, and a film of adhesive interposed between the glue lap and the
- 10 fourth panel for securing the glue lap thereto, the extension on the fourth panel having a score beginning at said film and extending angularly therefrom in alignment with the cut in the glue lap.
- 15 4. In a disposable bottle formed from a single unitary blank and comprising integral sides, a bottom and extensions carried by the sides adapted to be folded to form a top closure, a glue lap integral with one of the sides and its extension disposed adjacent a second side and its extension, said glue lap having a transverse knife score aligned with the junctures between said sides and extensions and an angular cut adjacent the knife score, a film of adhesive interposed between the glue lap and said second side and its extension, a score partially defining said extension from the second side extending toward the film, terminating at its point of intersection therewith and aligned with said knife score, and
- 20 5. In a disposable bottle formed from a single unitary blank and comprising integral sides, a bottom and extensions carried by the sides adapted to be folded to form a top closure, a glue lap integral with one of the sides and its extension disposed adjacent a second side and its extension, said glue lap having a transverse knife score aligned with the junctures between said sides and extensions and an angular cut adjacent the knife score, a film of adhesive interposed between the glue lap and said second side and its extension, a score partially defining said extension from the second side extending toward the film, terminating at its point of intersection therewith and aligned with said knife score, and
- 25 6. A blank for forming a disposable fluid container comprising a plurality of integral substantially rectangular panels adapted to form the container sides, panel extensions adapted to form a top-closure respectively defined from certain of the panels by transverse scores extending entirely across the latter, a glue lap extending longitudinally of one of said panels and its extension and defined therefrom by a longitudinal score the transverse score defining another extension from its panel being of less length than the width of the latter and terminating short of its outer edge a distance corresponding to the width of the glue lap, said last-mentioned extension having an angular score terminating a like distance short of said edge adapted to facilitate the folding of the extension in forming the top-closure and a film of adhesive extending longitudinally of said panel and its extension between said edge and the adjacent ends of said scores.
